UNITED STATES PATENT OFFICE.

STANISLAUS KUCHARSKI, OF BERLIN, GERMANY.

KEYBOARD MUSICAL INSTRUMENT.

Application filed April 1, 1925, Serial No. 19,932, and in Germany March 29, 1924.

This invention relates to a player device which can be attached to existing keyboard instruments, which owing to the special construction is more particularly suitable for manipulation by untrained lovers of music and chiefly constitutes a device for playing keyboard instruments according to individual feeling without any practice and knowledge of music, by simple means, owing to the possibility of controlling the time and the strength of sound.

This is attained chiefly by a specially advantageous construction of such a kind that, by depressing one or only a few keys by hand, on the one hand a music roll is advanced step by step, and on the other hand a pressure is exercised by means of auxiliary fingers on the keys to be played at the time, the said keys being switched in by a relay controlled by the music roll.

A construction of a player device according to the invention is diagrammatically illustrated in the accompanying drawing.

Fig. 1 shows the player device in front elevation, as placed upon the keys of a piano, the front covers of the casing being removed.

Fig. 2 is a sectional view on line 2—2 of Fig. 1.

Fig. 3 shows the music strip.

Fig. 4 is an enlarged detail.

According to this invention, a music strip (Fig. 3) is employed, which may be a thin band of celluloid, metal, paper or the like about 35 mm. wide, and is similar to a motion picture film or the like in having perforations 18 at its edges, which is employed to obtain the selection of the various keys to be depressed. Owing to the small size of this film, the whole player device may be built very narrow and easily attachable to the key-board of the instrument to be played.

A number of perforations 19 are formed in the music strip 8, and are arranged by groups of four rows in succession between each two successive perforations 18; that is, in the passage of the music strip through the device, four rows are presented beneath the selecting devices, and according to the perforations in these rows, the respective keys are prepared for actuation. The number of columns along the width of the strip may be determined at will according to the exact width of the strip and the size of the apertures, and according to the number

of keys which it is desired to control by the player device. Since there are four rows of keys, and in the present instance 22 columns, any number of keys up to 88 may be actuated at one and the same time or selectively as desired, singly or in chords according to the apertures arranged on the music strip 8.

The player device itself comprises a cabinet 1 having a top, front and rear walls, and a hood 27 arranged on its top. This hood has a hinged cover 29 which carries the contact block 20^a having a plurality of contact pins 20 seated fixedly therein, and in number equal to the number of keys to be played. These contact pins 20 are arranged in four rows at distances apart corresponding to the distances between the rows of apertures 19 on the music strip 8. It will be understood that these pins 20 are in electric contact with each other and are connected to a suitable source of electricity by the conductor 100. Each of these pins 20 is of substantially larger diameter than the thickness of the music strip, and has a spherical end, and is inclined both longitudinally and laterally with respect to the direction of movement of the strip; and as the strip moves between the blocks carrying the pins and the respective conductors 31, these pins revolve about their axes and ride over the edges of the perforations so that the strip continues in its movement (enlarged view of Fig. 4).

In the upper portion of the hood 27 is arranged a supporting table 30 of insulating material through which passes a number of conductors 31 equal to the number of keys to be played. These conductors are arranged in four rows, and in such manner that each conductor is presented exactly opposite one of the pins 20 with which it cooperates in the manner to be described hereinafter: they have a resiliency in their support so that when an aperture is presented between a pin and its respective conductor, these move into conductive relation; and when the strip material comes between them, they are forced apart, and the respective circuit is broken.

Likewise mounted in the hood 27 are the rolls 8^a and 8^b which carry the music strip 8. The music strip 8 passes from roll 8^a over the top of the supporting table 30, and between the contact pins 20 and the conductors 31, and into the space inside the

spring 32, and is wound up upon the roll 8^b in any suitable manner as by a spring device represented at 33. This movement occurs step by step by means of the gripper 9 which engages successively in the apertures 18 at the edge of the music strip 8. Each of the conductors 31 is connected to an individual electromagnet 26 as by the lead wire 102 in Fig. 2. These electromagnets are horizontally positioned within the casing 1 at a point substantially vertically above the key 5 which corresponds thereto. From this electromagnet, the circuit is completed back to the other pole of the source of electricity through a conductor 101. Fastened to the lower side of the rear wall of the casing 1 as by the posts 42 are a plurality of springs 41 which project forwardly and carry at their forward ends the bars 43. Similar fingers and springs are provided for the black keys, at a proper elevation above those described. The key fingers 4 are provided at their lower ends with the striking knobs 4^a of felt or similar material and are supported at the outer or front ends of the bars 43 as by curling the end of the respective key finger 4 and gluing a strip of felt to the external surface in well known manner. Each of the fingers 4 is positioned opposite its respective electromagnet 26, there being as many fingers as there are electromagnets and hence as there are keys to be played, which in turn is determined by the number of possible perforations contained within the four rows on the music roll 8.

Pivottally mounted within the casing 1 are the striking ledges 3^a and 3^b, which are similar in all respects, and are arranged end to end with a small gap 13 therebetween. It will be understood that more than two such striking ledges may be employed if desired; and that the purpose of the division between the ledges is to enable the fingers 4 to be depressed with differing forces at differing parts of the keyboard. Each of these striking ledges 3^a, 3^b is provided at its front end with a retaining flange 3^c (Fig. 2).

In order to depress the respective striking ledges 3^a and 3^b are provided the auxiliary keys 2 which are mounted upon key bars 2^a pivoted within the casing 1. Since the construction of these auxiliary keys and key bars is identical, only one has been represented in the figures. When the respective auxiliary key 2 is depressed, its key bar 2^a during its downward movement comes into contact with the respective striking ledge 3^a or 3^b and forces the latter downward. As shown in Fig. 2, the key bar 2^a is pivoted in the mechanism at 2^x and has a connection 12^a (Fig. 1) at the free end of the striking ledge 3^b, so that as the key 2 is depressed, the bar 2^a will act upon the ledge 3^b and

depress it in a clockwise direction about its pivot, which is shown as being the same pivot pin 2^x as that employed for the key bar 2^a. Accordingly as the respective electromagnets 26 have been energized or not, the fingers 4 corresponding to each electromagnet have been drawn into the dotted line position shown in Fig. 2 or have been left in the full line position. As the ledge 3^b in Fig. 2 moves downward it encounters the fingers 4 which have been moved into the dotted line position and drives them forcibly downward through depressing the respective piano keys 5. On the other hand, the unconnected fingers 4 as shown in full line in Fig. 2 remain unmoved during the depression of the auxiliary key 2.

When the auxiliary key 2 is released, it is returned, together with the operative striking ledge 3^a or 3^b by a recoil spring a.

In order to advance the music strip by a proper distance, the auxiliary key 2 is provided with means to actuate the gripper 9 at each successive depression. The key 2^a for this purpose has a gripping loop 2^b. The ledge 3^b has an upstanding pin 12^b with an enlarged head 12. A gripper lever 7 is pivoted upon the casing and hood at 10 and is pivotally connected at 16 to the gripper 9. The free end of the other end of the gripper lever 7 is fastened to a spring 11 which is presented beneath the head 12 and secured on the casing 1.

The gripper lever 7 swings about its fulcrum 10 upon the operation of the ledge 3^b, to cause the gripper 9 to engage and advance the music strip 8 by a stepwise movement which is of constant amount for each oscillation of the lever 7 and is independent of the movement of the ledge 3^b. Since the downward movement of the ledge 3^b may be of different amount for different instruments, according to the distance necessary to bring the striking fingers 4 into contact with the respective keys 5 and depress the latter, a stop 17 is provided to positively limit the amount of movement of the gripper lever 7, and a resilient connection 11, 12 is provided to take up the remaining or differential movement of the ledge 3^b. As the ledge is depressed, the member 12 encounters the spring 11 and at first rocks the lever 7 upon which the spring 11 is mounted in a clockwise direction until the lever 7 encounters the stop 17; thereafter the member 12 merely bends the spring 11 downward more or less until the ledge has completed its movement. The spring 11 upon release of the ledge serves to assist the return of the latter and the member 12 to the normal position. The gripper 9 is pivoted to the end of lever 7 upon a pin 16, and has a hook at its free end to engage in the equally spaced perforations 18 of the music roll. Each time the lever 7 moves

clockwise in Figure 1 as described above, the band 8 is advanced a single step of predetermined and equal amount, and as the lever 7 returns in a counter-clockwise movement, 5 the inclined end of the hook on gripper 9 causes it to leave the aperture 18 last engaged and move into operative relation with the succeeding aperture 18.

By striking either of the keys 2, the respective striking ledges 3^a and 3^b are actuated and cause the selected fingers 4 to depress their corresponding keys 5. By striking one of the keys 2 differently from the other key, the player is enabled to control the relative loudness of the melody or accompaniment. The right hand ledge 3^b strikes the keys for the high tones and that at the left, 15 3^a, strikes the keys for the low tones. This insures that the player is able to bring out 20 the melody or the accompaniment more strongly at his option: by striking the right hand auxiliary key in one instance and that at the left in the other. It will be noted that the plurality of striking ledges 3^a and 25 3^b are respectively positioned above divisions of the register of the keyboard, so that the bass and treble notes may be struck differently: the melody being brought out by the treble notes and the accompaniment by the 30 bass notes.

In order to introduce a music strip 8 into the apparatus, the cover 29 is raised and the music strip wound on the roll 8^a is placed in position; the outer end of the strip is brought over the supporting table 30 and the gripper 9, and engaged with the take-up roll 40 35 8^b in any suitable manner: it will be understood that the take-up roll 8^b is caused to rotate in any well known way. The cover 29 is now replaced so that the music strip is visible through the window 28.

The player device is generally placed on only a portion of the keyboard, for example over 70 keys, and the remaining keys remain without being played. In order to secure a correct setting of the player device on the keyboard of the piano, the strip ledges 39 and 40 are provided at the lower side of the casing 1. The ledges 40 are 45 fixed to the casing to project behind the non-played keys, to prevent the movement of the device forwardly or rearwardly, while the ledges 39 are situated between the black keys of the instrument and serve to determine the 50 position of the device against a movement to the right or left on the piano.

When the respective finger keys 5 have been actuated in the manner above described, and the music strip has been moved to a new 60 position in which a particular key is not to be actuated the circuit through the respective magnet 26 is interrupted by the presence of the thickness of the music strip between the respective contact pin 20 and the conductor 31, and hence the deenergized elec-

tro-magnet 26 will release its finger 4 which moves under the action of the spring and bar 41, 43 from the position shown in dotted lines to the position shown in full lines. Other electromagnets 26 may at this same 70 time be actuated to bring their respective fingers 4 into the range of action of the striking ledges 3^a, 3^b, according to the perforations 19.

It will be understood that at each depression of the striking key or auxiliary key 2, the music roll is advanced simultaneously with the downward movement of the respective striking ledge 3^a, 3^b, the ledge engages the actuating fingers 4 and causes the playing of the piano. At the same time, the music strip has been moved and the magnets 26 are energized so as to attract the proper fingers 4 for the next chord or note to be struck: these fingers are drawn 80 against the edge flange 3^c of the respective striking ledge, and are not actuated at the stroke. When the key 2 is permitted to return, however, the deenergized magnets 26 permit their fingers 4 to fly back, while the energized magnets 26 give a further movement to their respective fingers 4 so that the latter move into operative relation with regard to the respective ledges 3^a, 3^b. In this 85 way, each note or chord is set up while the preceding note or chord is being played.

As shown in Fig. 3, the perforations 19 corresponding to the several pins 20 and the respective conductors 31 are prepared in such relationship to each other that the perforations for the outer right hand row of pins in Fig. 1 for one note may lie between the positions of the perforations for other rows for other notes, and an overlap of the perforations occurs. In other words, the distance 100 of advancement by the pawl 9 is less than the longitudinal extension of the several rows of pins 20 with respect to the music strip: and this advancement occurs by such an incidental fraction of this extension that 105 as the music strip comes to a standstill following each advancement, different transverse lines of apertures are presented to the respective pins. If during the traveling movement of the strip, any pin should encounter an aperture at which it will not remain when the movement of the strip is completed an actuation of the corresponding finger will occur, but since the ledges 3^a, 3^b have been depressed, the respective fingers 4 110 thus energized will strike the edge of the respective ledge, and be held there temporarily by the respective electromagnet: and during the further movement of the music strip, the circuit will be broken so that the respective 115 finger 4 will be permitted to fly back prior to the raising of the ledge 3^b. By this arrangement of overlapping perforations, it is possible to have the rows of pins 20 separated a sufficient distance longitudinally of 120 125 130

the music strip as required by mechanical considerations: and yet keep the length of the music strip for a given selection at a minimum.

It is obvious that the invention is not limited to the specific form shown and described, but that it may be modified within the scope of the appending claims.

What I claim as my invention and desire to secure by Letters Patent is:—

1. A player device for key instruments comprising a frame, a plurality of striking fingers fulcrumed on said frame and disposed above respective keys, each of said fingers having a movable iron element, a respective electromagnet fixed to said frame to move said element, means to selectively energize the electromagnets according to the notes to be struck, and an actuating member to depress the selected fingers.

2. A player device for key instruments comprising a plurality of striking fingers disposed above respective keys, each of said fingers having a stem, a respective resilient support for each of said stems and fingers to permit the same to move bodily downward and to rock back and forth from front to rear with a normal bias into the front position, an actuating member to depress all fingers and stems which have been rocked to the rear and devices to rock selected stems to the rear said actuating member including means to hold non-selected stems from moving to the rear until said member disengages the selected fingers upon return from depressed position.

3. A player device for key instruments comprising a plurality of striking fingers disposed above respective keys, means to select said fingers controlled by a music roll and including an individual device for each finger to move the finger to an operative position when selected, means to depress the

selectively moved fingers to strike the corresponding keys, and mechanism moved by said depressing means to advance said roll for selection of the fingers for one note or chord during the striking of the preceding note or chord.

4. A player device for key instruments comprising a plurality of striking fingers disposed above respective keys, means to select said fingers controlled by a music roll and including an individual device for each finger to move the finger to an operative position when selected, means to depress the selectively moved fingers to strike the corresponding keys and mechanism moved by said depressing means to advance said roll for selection of the fingers for one note or chord during the striking of the preceding note or chord, said depressing means including devices to hold the non-selected fingers from movement into position for depression until said depressing means releases the selected fingers of said one note or chord.

5. A player device for key instruments comprising a plurality of striking fingers disposed above respective keys, means to select said fingers controlled by a music roll and including an individual device for each finger to move the finger to an operative position when selected, means to depress the selectively moved fingers to strike the corresponding keys and mechanism moved by said depressing means to advance said roll for selection of the fingers for one note or chord during the striking of the preceding note or chord, the whole register of the keyboard being divided into a plurality of parts, and said depressing means being provided with separate depressing devices for each division of the register.

In testimony whereof I have signed my name to this specification.

STANISLAUS KUCHARSKI.
